UNITED STATES PATENT OFFICE.

PETER STUART, OF EDINBURGH, COUNTY OF MID-LOTHIAN, SCOTLAND.

COMPOSITE PAVEMENT.

SPECIFICATION forming part of Letters Patent No. 269,480, dated December 19, 1882.

Application filed May 22, 1882. (No model.)

To all whom it may concern:

Be it known that I, PETER STUART, a citizen of the United Kingdom of Great Britain and Ireland, residing at Edinburgh, in the county of Mid-Lothian, Scotland, have invented a new and useful Improvement in Composite Pavement, of which the following is a specification.

My improvement is especially, though not exclusively, intended for application to sidewalks; and it consists in the formation in the surface of pavements of depressions of such a character that in stepping thereon the pressure of the feet will expel the air, causing a partial vacuum, which, supplementing the mechanical effect of the roughened surface, will operate to afford an additional hold to the feet and prevent slipping. This beneficial effect is greater when the pavement is wet, at which time pavements as ordinarily constructed with smooth or grooved surfaces are more than usually slippery.

In the accompanying drawings, Figure 1 is a plan view of a section of pavement illustrating my invention. Fig. 2 is a vertical section of the same.

A represents blocks of pavement—such, for example, as described in Letters Patent of the United States No. 248,526, granted to me the 18th of October, 1881, and No. 259,059, the 6th of June, 1882.

B represent pits or depressions, which I prefer to form rectangular on the upper sur-

face and tapering downward to points, thus constituting inverted pyramids. They may, if preferred, be of round or any other form which adapts them to operate in the manner described; but they must necessarily be of limited area, preferably not more than one-fourth inch in diameter, and must be of substantially even or level margin, and without grooves or extensions, which would permit the passage of air when the top of the aperture is covered by the foot. They are preferably not more than half an inch apart, so that a number of them may be under the sole of the foot at once; but of course the invention is not limited to a specific distance, so long as they are sufficiently near to have the effect described.

This invention is applicable to artificial stone of all kinds, and to asphalt and all other kinds of plastic or composite pavements.

Having thus described my invention, the following is what I claim as new therein and desire to secure by Letters Patent—

A composite pavement formed with circular, square, or analogous depressions of equal or nearly equal diameter in each direction, and with even or level margin on the pavement surface, to adapt them to operate in the manner described.

PETER STUART.
